UNITED STATES PATENT OFFICE

101,254

DESIGN FOR AN EMBROIDERED FABRIC

Adolph Lehmann, New York, N. Y.

Application August 26, 1936, Serial No. 64,571

Term of patent 3½ years

To all whom it may concern:

Be it known that I, Adolph Lehmann, a citizen of the United States of America, residing in Manhattan, county of New York, and State of New York, have invented a new, original, and ornamental Design for an Embroidered Fabric, of which the following is a specification, reference being had to the accompanying drawing, forming part thereof, wherein,

The figure is a plan view of a piece of embroidered fabric showing my new design.

I claim:

The ornamental design for an embroidered fabric, substantially as shown.

ADOLPH LEHMANN.
